UNITED STATES PATENT OFFICE.

EMMA HIGDON, OF ELWOOD, INDIANA.

TURNING-SHEET AND PAD.

1,334,901.

Specification of Letters Patent. Patented Mar. 23, 1920.

Application filed December 10, 1918. Serial No. 266,154.

To all whom it may concern:

Be it known that I, EMMA HIGDON, a citizen of the United States, residing at Elwood, in the county of Madison and 5 State of Indiana, have invented new and useful Improvements in Turning-Sheets and Pads, of which the following is a specification.

This invention relates to a hospital appliance and is in the nature of a turning sheet.

The object of the invention is to produce an article of this character whereby a patient may be turned in a bed with the 15 least amount of physical exertion on the part of the nurse and with the least inconvenience to the patient.

A further object of the invention is to produce an article of this character which 20 shall be of an extremely simple construction, cheap to manufacture and thoroughly efficient for the purpose for which it is devised.

The foregoing objects may be accomplished by a simple construction and arrangement of parts illustrated by the drawings and set forth in the following description.

In the drawings:

30 Figure 1 is a perspective view illustrating the improvement and the method whereby the patient is turned thereby;

Fig. 2 is a plan view of the improvement; and

35 Fig. 3 is a sectional view approximately on the line 3—3 of Fig. 2.

Patients inflicted with certain maladies or diseases are incapable of exercising influence over their body or limbs, so that 40 when arranged in one position upon a bed they can not turn themselves to another position. The turning of the patient to a more restful position, with the ordinary methods requires the handling of the patient which is very painful to the patient and requires a great amount of physical exertion upon the part of the nurse.

With my improvement I arrange my turning sheet on the bed, transversely thereof 50 so that the same underlies the patient from beneath the nape of the neck to below the

hips. The sheet is of a materially greater length than the width of the bed, and consequently the ends thereof lap over the sides of the bed. The turning sheet comprises a fabric sheet proper which is indicated by the numeral 5 and which is preferably constructed of comparatively stiff and strong material and which has arranged thereover a pad 6. The pad is of a less 60 length than the sheet terminating approximately equi-distant from the ends thereof, but is of a width approximately equaling that of the sheet. The pad 6 is made up of absorbent cotton between layers of cheese 65 cloth or some other soft material and may be fastened to the sheet 5 by safety pins or by other means whereby the pad may be removed from the sheet. The under face of the pad is preferably tufted, but the outer 70 face thereof is smooth so as to offer a soft compressible cushion for the patient. The pad 6 is also of a greater length than the width of the pad, and by reference to Fig. 1 of the drawings it will be seen that by 75 grasping one of the ends of the sheet 5 by the nurse and exerting a pull upon the said sheet the patient may be turned to any desired degree or angle on the bed, in either direction, to best suit the comfort of the 80 patient.

Having thus described the invention, what is claimed as new, is:—

A turning sheet for hospital beds, comprising a fabric sheet designed to be arranged transversely of the bed, said sheet being of a greater length than the width of the bed, the sheet having a pad on the outer face thereof which terminates inward of the ends of the sheet and provides gripping portions at the said ends of the sheet, the pad designed to receive thereon the body portion of a patient and by virtue of the weight of the patient to be depressed at the portion thereof on which the patient rests to afford a frictional engagement with the patient and causing the patient to be rolled on the pad when a pull is exerted on either of the gripping end portions of the sheet. 90

In testimony whereof I affix my signature.

EMMA HIGDON,
